SHOE CONSTRUCTION

William Alfred Evans, Melfort, Saskatchewan,
Canada

Application October 23, 1944, Serial No. 559,998

1 Claim. (Cl. 36—3)

This invention relates to footwear and more specifically to the construction of shoes or boots whereby the circulation of air within the shoe is enhanced by mechanical means.

It is a well known fact that footwear, particularly rubber soled footwear, becomes exceedingly hot, causes great discomfort and may aggravate foot trouble during warm weather. Many devices to provide proper circulation within the shoe have been attempted, the most notable being the perforated shoe wherein the shoe upper is honey combed with small perforations. This device permits air to enter the shoe but fails to entirely meet the objectionable characteristic because there is no forced circulation. In addition the shoe is impracticable for children or under working conditions because sand or dust particles of all kinds readily pass through the perforations into the shoe.

This invention has for its principal object the provision of a shoe which causes air currents or the circulation of air around the foot of the wearer. I have shown two embodiments of the invention substantially similar as to principles of operation.

Another object of the invention is to utilize the alternating pressure of the foot on the inner sole and heel of the shoe to set up the air currents to the end that no foreign agent is necessary to bring about the desired results other than the shoe structure itself of course.

Still another object of a specific embodiment of the invention is to provide a circulating current of fresh air continuously passing through the shoe. A further object complementary to the foregoing objects is to arrange that the source of the air currents is located in the inner sole and inner heel adjacent the sole and heel of the wearer rather than on the top of the foot where its value is lessened.

Other objects of a more general nature are to provide a structurally simple, durable and comparatively inexpensive shoe of the character set forth.

With the above noted and other objects in view which may appear as the description proceeds the invention resides in the novel construction, combination and arrangement of corresponding parts as hereinafter more specifically set forth, claimed and shown in the accompanying drawings forming part of this application and in which:

Fig. 1 is a side elevational view shown partly in section of a shoe constructed according to my invention.

Fig. 2 is a sectional view taken along the line 2—2 of Figure 1.

Fig. 3 is a side elevational view of a modified construction shown partly in section.

Fig. 4 is a fragmentary sectional view taken on the line 4—4 of Figure 3.

Fig. 5 is a detailed view of the toe portion shown in Figure 3.

Fig. 6 is a fragmentary front elevational view of a shoe constructed according to Figure 3, and

Fig. 7 is a fragmentary detailed view of the heel portion constructed according to Figure 3.

Referring more in detail to the drawings in which similar reference characters designate corresponding parts throughout the several views it will be seen that the invention of Figures 1 and 2, consists of a shoe upper 10, of any suitable design and materials. Broadly speaking the upper is secured to the sole in the usual way, due regard being given to the materials used, none of which are unknown to the art of shoe manufacturing.

The inner sole 11, to which the upper is secured consists of a corded rubber member of suitable shape through which a great number of relatively large perforations 12, are cut. It is advisable that the perforations be as large as possible although necessary that they be limited in size so that they will cause no annoyance to the sole of the wearer's foot.

The outer sole and outer heel of this type of shoe are formed integral, with the instep recessed slightly if at all. The material consists of a sponge rubber intermediate portion 13, having a processed air-tight outer wall 14. The outer wall may consist of an air-tight skin vulcanized to the sponge rubber. A standard hard rubber outer portion 15, is joined to the portion 13, to protect the sponge rubber and to provide an efficient tread for the shoe. The various components are or may be vulcanized together or joined in any suitable manner according to the dictates of known manufacturing methods.

The device functions in the following manner:

While walking, when the shoe is placed on the ground the pressure on the sponge rubber 13, caused by the weight of the person being centered on that foot, forces the air out of the air cells in the sponge rubber, through the perforations 12, of the inner sole 11, and around the foot of the wearer. When the shoe is raised from the ground the pressure on the sponge rubber is removed and a partial vacuum set up in the said rubber causing the air in the shoe (and to an extent, air from outside the shoe) to pass back

through the perforations into the air cells of the sponge rubber. The airtight walls prevent the air from escaping except through the said perforations. From the foregoing it will be seen that a continuous circulation of air is set up within the shoe during the progressive raising and lowering of the shoe to and from the ground surface.

In the modification shown in Figures 3 to 7, inclusive, the device consists of the usual upper 10, of any desired material and design. The upper is secured in the usual way to an inner sole 16, which is substantially similar to the inner sole of Figure 1, including the perforations 12. The exception resides in the additional air passages 17, disposed in the toe portion of the inner sole which permit air from the interior of the shoe to pass through to the outside. The construction and arrangement of the air passages are most clearly seen in Figures 5 and 6. The outer sole and heel of this construction is similar to the construction of Figure 1, consisting of an intermediate sponge rubber portion 13, and an outer hard rubber portion 15, all secured together in the usual manner.

An air-tight sleeve, preferably a relatively hard rubber sleeve 18, is disposed down the back or heel portion of the upper and is secured to the inner sole 16, and to the sole 15, at 19, and 20, respectively, the intervening side areas are cemented or attached in any suitable air-tight manner to the sole 13; thus the mouth of the tube 18, encloses an area of the said sole 13. It is important to note that the wall of the sole 13, enclosed in the mouth of the tube is not air-tight to the end that air passing through the tube 18, will enter the air cells of the sponge rubber sole 13. A one way valve 21, is disposed in the tube 18, to the end that air may be drawn into the said tube but will not be permitted to escape out of the tube. I have shown a simple and relatively efficient valve consisting of two flaps formed integral with the inner wall of the tube which will bend downward against the said wall but will not bend upward; when air forces the flaps upward their free ends abut in a substantially air-tight manner. An outer reinforce-

ing, protective cover 22, is provided to support and protect the tube 18.

The invention of Figure 3 functions in the following manner:

5 While walking, when the shoe is placed on the ground the pressure on the heel of the shoe causes the air in the cells of the sponge rubber member to be expelled through the perforated inner sole and into the shoe, the pressure progressively rolls forward and a considerable amount of air is expelled through the air passages 17. As the pressure rolls forward to the ball of the foot of the wearer a partial vacuum is set up in the heel portion of the sponge rubber sole 13, and air is drawn through the tube 18, to fill the air cells of this member. The walls of the tube must be strong enough to remain rigid when air is passing therethrough. The shoe is lifted then replaced to the ground whereupon the action is repeated thus causing a circulation of fresh air through the shoe as each step is taken.

15 It is believed that the construction and advantages of the structure shown may be apparent from the foregoing paragraphs taken in conjunction with the accompanying drawings without further detailed description.

20 While the preferred embodiment of the invention has been disclosed it is understood that minor changes in the construction, combination and arrangement of co-operating parts may be resorted to within the scope of what is claimed without departing from the spirit of the invention.

25 I claim:

30 A shoe construction comprising an upper, an inner sole having a series of perforations therethrough, an outer sole, a relative thick resilient cellular sole disposed intermediate the inner and outer soles and having an air-tight outer wall, 35 passages through the forward end of the inner sole establishing communication between the inside of the upper and the atmosphere, an air inlet tube extending vertically of the rear end of said upper and connected at its lower end with 40 said intermediate sole and a one way flap valve 45 in the upper end of said tube.

WILLIAM ALFRED EVANS.
